UNITED STATES PATENT OFFICE

2,495,855

TURBINE IMPELLER WHEEL

Reuben James Marcoe, Hermansville, Mich., as-
signor to Furbie Company, Hermansville, Mich.

Application July 17, 1946, Serial No. 684,326

1 Claim. (Cl. 253—77)

1

This invention relates to turbine impeller wheels and more particularly to the manner of attachment of impeller blades to the frame of the rotor.

An object of this invention is to provide an improved impeller blade for certain types of impeller construction and an improved means of attachment of the blades to the peripheral rotor discs.

Another object of this invention is to provide an improved means of attaching axially disposed impeller blades to the annular rotor frame members by providing a notch in the outer ends of each blade and a tab or ear which is adapted to be bent over and attached by welding or other suitable attaching means to the outside surface of the rotor frame discs or rings thereby increasing the effective blade area between the rings and providing a substantial attaching means for the blades.

Still another object of this invention is to provide an improved impeller blade construction whereby the full area of the blade between the supporting rings is utilized as on a pump for air in air conditioning units.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a top perspective view, partly broken away of a series of impeller blades constructed and attached to a rotor ring according to an embodiment of this invention.

Figure 2 is an end elevation, and

Figure 3 is a front elevation of the blades in Figure 1.

Referring to the drawings the numeral 10 designates generally an impeller blade of the type generally used in air pumps provided in air conditioning units for forcing air through the ducts of the air conditioning system. Heretofore many different types of fans and impellers have been used on such systems and it has been found that an impeller of the nature of a turbine, as shown in the attached drawings, is the most efficient and satisfactory type of pump. There have been many ways of constructing the blades for such pumps or turbines at the ends of the blades to

2

the rotor rings, designated generally by the numeral 11, and such methods of attachment require considerable machine work on the blades 10 and rings 11 and tedious methods of accurately locating the blades 10 about the periphery of the rings 11, resulting in the high cost of manufacture and assembly of such rotors for these turbines. By the construction of blades 10 according to an embodiment of my invention the blades may be stamped into the desired shape or otherwise formed without the use of laborious and expensive machining of the blades 10 or the ring 11 and the blades may be readily positioned accurately by a simple fixture or template.

15 The blades 10 are formed of an elongated strip of metal of an arcuate cross section which extend axially about the rotor of the turbine and are fixed at each end to an annular flat ring 11. The ring 11 is supported about the rotor of the pump, not shown, concentric to the shaft of the impeller.

15 Each blade 10 is formed, before assembly, with a substantially rectangular notch 12 on each end thereof which extends forwardly from the rear 25 or trailing edge of the blade 10 approximately one half the width of the blade 10, thereby providing a remaining ear or tab 14 which extends outwardly longitudinally from the forward portion of the blade 10, which tab 14 is adapted to be bent over the peripheral edge of the ring 11.

25 In assembly the blades 10 are positioned in engagement with the inner face of opposite rings 11 with the arcuate inner edge of the notch 12 abutting the inner face of the ring 11 whereby the tab 14 overlies the peripheral edge of the ring 11. The tab or ear 14 is then bent or folded over the ring 11 to engage in face abutting relation the outer face of the ring 11 and the tabs

30 14 are welded as at 15 to the ring 11 with the front or leading edge of the blade or vane 10 raised above the periphery of the ring 11, and the rear edge of the tab 14 engaging the peripheral edge of the ring 11 in the inner forward corner of the notch 12.

35 By a blade or vane construction of this type the cost and time required may be substantially lessened and the manner of attachment is simple and more efficient as regards strength and installation time and expense.

40 I do not mean to confine myself to the exact details of construction herein disclosed but claim all variations falling within the purview of the 45 appended claim.

Having thus described my invention, what I claim is:

An improved turbine wheel comprising a pair of spaced apart concentric annular rings, a plurality of axially disposed blades fixed on said rings and extending therebetween, each of said blades being formed of an elongated arcuate strip of metal, a rearwardly and outwardly opening notch cut in each of the opposite corners of the trailing edge of said blade to provide an attaching ear on each end thereof as a continuation of the leading edge of said blade, said ears being bent at right angles to the remainder of said blade over the periphery of the adjacent rings and engaging and secured to the outer faces of said rings, said leading edges being disposed above said periphery and said remainder of said

blades being inclined towards the axis of rotation of said rings.

REUBEN JAMES MARCOE.
